CLAIM

The ornamental design for a mounting jig, as shown and described.

DESCRIPTION

FIG. 1 is a perspective view of a mounting jig;

FIG. 2 is a rear elevational view thereof; and

FIG. 3 is a front elevational view thereof;

FIG. 4 is a top plan view thereof;

FIG. 5 is a bottom plan view thereof;

FIG. 6 is a left elevational view thereof; and,

FIG. 7 is a right elevational view thereof.

The broken lines in the figures form no part of the claimed drawings.
